P. L. KIMBALL.

APPARATUS FOR USE IN CLEANING CREAM SEPARATOR SECTIONS.

APPLICATION FILED JAN. 8, 1912.

1,043,606.

Patented Nov. 5, 1912.

UNITED STATES PATENT OFFICE.

PERLEY L. KIMBALL, OF BELLows FALLS, VERMONT, ASSIGNOR TO VERMONT FARM MACHINE COMPANY, OF BELLows FALLS, VERMONT.

APPARATUS FOR USE IN CLEANING CREAM-SEPARATOR SECTIONS.

1,043,606.

Specification of Letters Patent.

Patented Nov. 5, 1912.

Application filed January 8, 1912. Serial No. 670,097.

To all whom it may concern:

Be it known that I, PERLEY L. KIMBALL, a citizen of the United States, residing at Bellows Falls, in the county of Windham 5 and State of Vermont, have invented a certain new and useful Improvement in Apparatus for Use in Cleaning Cream-Separator Sections, of which the following is a full, clear, and exact description.

10 The primary object of this invention is to provide means for readily and thoroughly cleaning the "sections" which constitute the skimming device or skimmer of cream separators, and especially for so cleaning the 15 sections in the condition in which they must be arranged or assembled for use in the separator bowl, without disassembling or detaching them from one another but merely removing them intact from the bowl.

20 The invention consists of a twirling device having a head which may be readily applied to the sections when they are assembled as for use so that the sections or skimming device or skimmer may be immersed 25 in any cleaning fluid, such as water, in a pail or other receptacle, and rapidly turned back and forth until thoroughly cleaned in every part, and so as to be ready for use again in the separator, after any 30 usual scalding and drying, when these last-mentioned operations are necessary or desirable, all as I will proceed now more particularly to set forth and finally claim.

In the accompanying drawings illustrating 35 the invention, in the several figures of which like parts are similarly designated, Figure 1 is a perspective view of the device detached. Fig. 2 is a perspective view of the device applied to a series of sections united 40 and constituting the skimming device or skimmer, illustrating the method of use. Fig. 3 is a horizontal section taken substantially in the plane of line A B, of Fig. 1, with part of the top plate broken out to 45 show the curved blades. Fig. 4 is a side elevation of the twirler parts shown in Fig. 3 with a portion of the head broken away, and a skimmer part in section. Fig. 5 is a cross-section taken at right angles to the 50 section in Fig. 4. Fig. 6 is a bottom plan view of the head.

1 is a hand-grip on a frame 2. This frame 2 is provided with bearings 3 and 4 for a longitudinally-arranged shaft 5, on which 55 is fixed a bevel gear 6, suitably held in place

within the frame 2 and meshing with a bevel gear 7, which is mounted upon a stud-shaft 8, secured in the frame 2. This bevel gear 7 is provided with a handle 9 by which said gear may be turned in either direction, 60 so as to turn shaft 5 through its bevel gear 6. Fixed to the bottom of shaft 5 is a head 10, having the parallel notches 11, and a vertically-arranged spring pin 12.

The apparatus above described constituting the twirling device hereinabove referred to, is designed for use in connection with a stack or nest of separator sections 13, shown in Fig. 2, and indicated in Figs. 3, 4 and 5. These sections are connected by a pair of 70 rods 14, and the stack or nest of sections so arranged upon these rods is secured by means of thumb-nuts 15 applied to the rods above and bearing upon the outermost section, the whole constituting the skimming 75 device or skimmer.

The notches 11 of head 10 are wide enough to straddle the thumb-nuts 15 on the rods 14, and when the sections are removed from the separator bowl, the twirling device is applied thereto by slipping the head 10 across the top of the sections so that its notches will engage the thumb-nuts 15, and until the spring pin 12 snaps into an opening in the topmost section, as shown in Figs. 4 and 5, 80 so as to clamp the head and its superposed parts upon the sections in such way that the sections as a whole may be revolved back and forth by appropriately turning the handle 9 while the frame 2 is grasped by the operator, all substantially as indicated in 85 Fig. 2. To wash or clean the sections, they are inserted in a pail or dish or other vessel containing enough water to cover the sections, and then the twirling device is turned 90 in one direction rapidly, and then as rapidly turned in the other direction, so that the centrifugal force exercised in connection with the involute curvature of the blades 16 which form parts of the sections will serve 95 to thoroughly rinse or cleanse the sections.

The invention is herein shown and explained in connection with a skimming device or skimmer constructed in accordance 100 with my invention patented May 4, 1909, No. 920,481. As shown in that patent, the sections, or as therein termed, the sub-dividers, comprise perforated plates 17 and the curved blades 16, the blades of adjacent sections interlocking. In the present inven- 110

tion the upper section has its plate 17 reinforced at 18 on opposite sides of its central opening 19, and these reinforces 18 are perforated to receive the reduced tubular extensions 20 of the thumb-nuts 15, and these nuts are provided with the collars 21 which rest upon said reinforces 18. The notches 11 straddle these shoulders beneath the heads of the thumb-nuts. The opening 19 is the 10 opening hereinabove referred to into which the spring pin 12 snaps in order to locate the head.

The head 10 is recessed on its underside to form parallel flanges 22, or these flanges 15 may be otherwise provided, and they align with the edges of the reinforces 18 and thus aid in holding the head in engagement with the skimmer.

Thus is furnished a very simple and efficient self-contained and portable cleaning device, with few parts, and readily applicable to the object to be cleaned. Of course, the head 10 or other medium for effecting a connection with the article to be cleaned will 20 be modified within the principle of the invention as hereinafter claimed in such manner as to be readily applicable to the object or article to be cleaned and as readily detached therefrom.

30 What I claim is:—

1. The combination with a handle and frame, of a shaft, and means to rotate it mounted upon said frame, and a head secured to the shaft and provided with notches 35 and a vertically disposed detent for detachably connecting it rigidly with an article to be cleansed by imparting thereto rotary motion.

2. An apparatus for use in cleaning cream 40 separator sections, same comprising a frame, a shaft mounted therein, means on the frame to rotate said shaft, and a head fixed to the end of the shaft and turning therewith, and having notches and a spring pin for engaging the article to be cleaned.

3. In an apparatus for use in cleaning

cream separator sections having extensions thereon, a head having notches to engage said extensions on the sections, and means to fix the engagement of the head with said 50 sections, in combination with means to rotate said head and its attached sections.

4. In an apparatus for use in cleaning cream separator sections, without disassembling the sections, a head adapted to engage 55 the assembled sections, and interlocking means to locate said head in engaging position on the sections, combined with means to rotate the head and sections in any desired direction.

5. In an apparatus for use in cleaning the assembled sections constituting the skimmer of a cream separator, the uppermost of said sections having projecting parts and an opening, a head having notches to engage 65 said projecting parts, flanges to coöperate with adjacent parts of the sections, and a spring pin to engage said opening, combined with a head rotator.

6. An apparatus for use in cleaning cream 70 separator skimmers comprising a head having parallel notches and a vertically disposed spring detent adapted to be connected with the skimmer, a supporting frame for said head, and means to actuate said head 75 in said supporting frame so as to impart a twirling motion to the skimmer.

7. A self-contained, portable apparatus for use in cleaning a cream separator skimmer, comprising a frame, a head mounted in 80 said frame, means to impart a twirling motion to said head in said frame, and means on the head adapted to engage coöperating means on the assembled skimmer for locking it transversely and longitudinally with the 85 skimmer.

In testimony whereof I have hereunto set my hand this 5th day of January A. D. 1912.

PERLEY L. KIMBALL.
